J. Stuart Franklin,
ATTORNEY.

UNITED STATES PATENT OFFICE.

ROBERT ARCHER, SR., OF FORT WASHINGTON, PENNSYLVANIA.

DOORCHECK.

Application filed March 31, 1925. Serial No. 19,559.

To all whom it may concern:

Be it known that I, ROBERT ARCHER, Sr., a citizen of the United States, residing at Fort Washington, in the county of Montgomery 5 and State of Pennsylvania, have invented certain new and useful Improvements in Doorchecks, of which the following is a specification.

The object of this invention is to provide 10 improvements in door-checks, and particularly those designed for the primary purpose of arresting the rapid movement of a door in closing, and then permitting the door to continue its closing movement in 15 such manner as to prevent noise or a slam.

Another object is to provide in such an article, a means constituting a rubber or similarly resilient member which with repeated use of the check, automatically rotates or otherwise shifts its position in such a way as to constantly alter its point of contact with the door, and thereby insure a uniform though retarded wear of the said resilient member.

25 A further object is to provide an improved support for the resilient member, which at the same time constitutes a partial housing for the same, into which the said member retreats when in contact with a door, and 30 which housing normally serves as a shelter to protect the said member from rain, snow, sleet, and sun.

Still another object is to provide a construction for such a check, that the housing 35 member may be reversed with little effort, to make it adaptable for use on either right- or left-hand doors, and the check supporting plate being reversible without alteration.

And a still further object is to provide an 40 attachment for a door, adapted to co-operate with the improved check, so as to more efficiently operate the latter by more positively engaging the resilient member of the check, and permitting the check to be positioned in a more recessive position upon the 45 jamb, than when no such attachment is employed.

With these and other objects in view, the 50 present invention comprises additional novel details of construction and operation herein-after fully brought out in the following description, when read in conjunction with the accompanying drawings, in which Fig. 1 is a side elevation of the improved check in its 55 nominal position upon the jamb of a door-frame; Fig. 2 is a similar view of the check

but in its retracted position due to co-operation with the door as indicated; Fig. 3 is an end elevation of the check in the position shown in Fig. 1; Fig. 4 is a horizontal section of the check on the line 4—4 of Fig. 1, but with the resilient member in plan; and Fig. 5 is a side elevation of the door attachment shown in co-operation with the resilient member of the check. 60 65

Referring to the drawings, the jamb of a door-frame 1 is shown as being provided with a recessed portion 2 in which the adjacent edge portion of a door 3 is adapted to be positioned when closed. 70

To the frame 1 is secured by any suitable means a plate 4, having a boss 5 into which is removably secured one end portion of a stud 6, having an enlarged head 7 upon its outer end, in order to retain upon said stud 75 the hollow supporting member and resilient means, constituting the principal parts of the check.

The supporting member referred to comprises parallel side walls 8 and 9, through 80 both of which the said stud extends, and which are connected by a rear wall 10 and end walls 11 and 12. There also extends between the side walls a second stud 13, which does not protrude beyond said walls, but 85 which, like the first-mentioned stud, carries a sleeve 14.

A third stud 15 extends between parallel 90 projections 16 of each of the said side walls, and passes loosely through the centrally positioned enlarged aperture 17 of an annular ring 18 of rubber or other suitable resilient material. This ring extends partially into the supporting member, which also serves as a housing for the same, yet normally projects sufficiently therefrom to engage a door, as the latter in closing reaches the position shown in Figs. 1 and 4. 95

This operative position of the check is 100 normally maintained by the weight of the housing member about the pivotal stud 6, causing the rubber ring to project forwardly, yet further movement in this direction is prevented by the engagement of the lug 19 with a lug 20, carried by the plate 4. The 105 lug 19 comprises an integral extension from the small plate 21, which is removably secured to the ring-supporting member in such position that when used for a door which swings in one direction, the lug projects laterally in one direction, and reversal of the 110 disc causes the lug 19 to project in the op-

posite direction, in order for the check to be accommodated to a door which swings in the opposite direction.

In operation, when a door abruptly engages the rubber ring with a smart blow, the latter is forced suddenly inwardly of the housing member and engages the sleeves 14 and the edge portion 22 of the upper end wall 11. The elastic ring being firmly engaged by the edge 22 and thus prevented from turning, the check cannot recede, and the movement of the door is arrested. However, while the door is on the rebound, due to the resiliency of the ring, the ring becomes loosened from the edge 22 of the wall 11, and upon the door's again engaging said ring but with less suddenness and more easily than before, the ring and its supporting housing oscillate upon the stud 6 into the position shown in Fig. 2, since the surface of the ring slides over the edge 22 without being indented by the latter. The check is prevented from turning much farther than the position there shown, due to a lug 23, formed integrally with the housing member, engaging the lug 20. Incidentally, there are two oppositely projecting lugs 23, to accommodate the device to right- and left-hand doors, as in the case of the plate 21 and lug 19.

In some instances it has been found advantageous to set the check much farther inwardly of the door-frame, and also to increase the frictional contact between the door and the rubber ring. In such cases, the attachment shown in Fig. 5 is secured to the door. This attachment comprises a body portion 24, secured in any suitable manner to the door, and provided with a series of teeth 25, corrugations, or the like, which directly engage the ring 18 as the door swiftly closes and cause the check to operate in the manner hereinbefore described. From either arrangement, namely, the door with or without the said attachment, the weight of the housing member causes the check to oscillate upon the stud 6, as the door is opened, and the ring moves into the extended or operative position shown in Figs. 1 and 4.

Having thus described my invention, what I claim and desire to protect by Letters Patent of the United States is:—

1. A door check, comprising a hollow

member, means for pivotally mounting said member upon a door jamb, means to limit the oscillatory movement of said member with respect to said first means, and a resilient member carried loosely by and extending from within said first member and adapted to cooperate with a door while the door approaches and thereafter remains in closed position.

2. A door check, comprising a hollow member, means for pivotally mounting said member upon a door jamb, means to limit the oscillatory movement of said member with respect to said first means, and an annular rubber member having an enlarged central aperture, and means carried by said first member and extending loosely through said aperture to support said rubber member and to permit the rubber member to freely alter its position with respect to said first supporting member.

3. A door check, comprising a hollow member having side and end walls, a bar extending between the side walls, a rubber ring, having an enlarged central opening through which said bar passes, and extending into said member, means to support said member upon a door frame, and when a door engages said ring, a portion of said ring being forced into temporary binding engagement with one of the end walls of said member, and thereby arresting the movement of the door.

4. A door check, comprising a hollow member having side and end walls, a bar extending between the side walls, a rubber ring, having an enlarged central opening through which said bar passes, and extending into said member, means to pivotally support said member upon a door frame and to limit the oscillatory movement of said member, so that when a door rapidly engages said ring, a portion of said ring is forced into temporary binding engagement with one end wall of said member to arrest the movement of the door, said member and ring then oscillating into a retreating position to permit the door to continue its movement and close in the frame.

In testimony wherof I have affixed my signature.

ROBERT ARCHER, Sr.
